APPARATUS FOR ALTERING THE TEMPERATURE OF GRANULAR MATERIAL

Royal M. McShea, Wichita, Kans.

Application January 19, 1948, Serial No. 3,054

2 Claims. (Cl. 257—6)

1

This invention relates to apparatus for preconditioning sand by altering the temperature thereof for incorporation with other ingredients in a concrete mix.

In concrete construction, especially in large projects such as the construction of large dams and the like, it has been found that the sand for the concrete mix that is necessarily exposed to different climatic conditions at the construction site sometimes becomes too hot and at other times too cold to be incorporated with the other ingredients in the concrete mix. By having the mixing temperature of the concrete uniform, expansion and contraction of the mixture is decreased, thereby lessening the danger of expansion cracks.

An object of the invention is to provide a means by which the temperature of sand can be economically and rapidly altered for use in a concrete mix.

Another object of the invention is to provide a continuous means whereby the temperature of sand can be economically and expeditiously altered to that suitable for incorporation in a concrete mix and which can be practiced on a large scale to meet the demands of concrete construction of great magnitude.

Another object of the invention is to provide an apparatus of simple, compact construction that will operate efficiently to carry out the method.

The invention, with other objects and advantages thereof will be understood from the following detailed description, when considered in connection with the accompanying drawing forming part hereof and illustrating a preferred form of apparatus for practicing the method.

In accordance with the invention, the sand to be preconditioned by altering the temperature thereof is continuously supplied to a receptacle from the bottom of which the sand is discharged in a multiplicity of small streams into the upper ends of vertically extending metal pipes surrounded by a heat interchanging liquid, the sand dropping by gravity through and in contact with the walls of the vertical pipes. The vertical pipes extend through a closed chamber that holds the heat interchanging liquid. Cold or hot water is continuously circulated through the closed chamber about the vertical pipes depending upon whether the temperature of the sand is to be lowered or is to have its temperature raised.

The treated sand flowing from the lower ends of the vertical pipes is collected in a receiving vessel and from thence transferred to a concrete

2

mixing plant of conventional construction, the sand being fed into the plant in proper proportion with the other ingredients forming the concrete mix.

5 In the drawing, is shown in vertical section an apparatus constructed in accordance with the present invention. The particular construction illustrated comprises an elongated vertically extending casing 1 open at its upper end and separated by transverse partitions 2 and 3 into an upper vessel 4 for receiving the sand to be cooled, a closed intermediate chamber 5 for a heat interchanging liquid, and a lower compartment 6. The partitions 2 and 3 are provided with apertures 7 in which are fitted and suitably secured to the partitions the ends of vertically extending pipes 8, the pipes communicating at opposite ends with the upper vessel 4 and lower compartment 6 and forming vertical passages or 10 conduits leading from the upper vessel 4 through the closed intermediate chamber 5 to the lower compartment 6. The lower compartment 6 has a sloping bottom wall 9 and a material outlet 10 in the side wall thereof at the lower end of its sloping bottom wall 9 with a discharge spout 11 extending laterally from said outlet. 12 designates a vertically slideable gate or valve for the material outlet 10. Any suitable operating means, not shown, is provided for opening and closing the gate or valve, and for holding it in different intermediate positions of adjustment to regulate the discharge of material from the lower compartment 6. The casing 1 is shown supported upon beams 13.

15 Apparatus is provided for cooling and heating water for use in the intermediate chamber 5. This includes a tank 14 with a refrigerating unit 15 and a heating unit 22. Both the refrigerating unit 15 and the water heating unit 22 are of conventional construction and are only indicated in a general way in the drawings. Any of the well known conventional forms of refrigerating units and water heating units suitable for the purpose may be employed. The refrigerating unit 15 has a cooling coil 16 located within the tank 14 connected with the refrigerating unit 15 by pipes 29 and 30, in which pipes are valves 31, 32 providing for closing off communication of the cooling coil 16 with the refrigerating unit. 15' designates an electric motor for operating the cooling unit. The water heating unit 22 has a water chamber that is heated by an oil burner operated in the regular way by an electric motor 23. When the motor is in operation, the oil burner of the heating unit will be

operated to heat the water and generate steam. 24 designates a pipe leading from the steam space of the heating unit 21 into the tank 14, said pipe having suitable outlet nozzles 25. 26 is a return pipe connection from the water tank 14 to the water chamber of the water heating unit. In the pipes 24 and 26 are valves 27, 28 for closing off communication of the liquid heating unit 22 with the tank 14. 17 designates a pipe connection leading from the tank 14 to the lower end of the intermediate chamber 5, and 18 is a return overflow pipe connection leading from the upper part of the intermediate chamber 5 back to the tank. A centrifugal pump 19 is interposed in the pipe connection 17 for forcing water from the tank 14 to the intermediate chamber 5, the apparatus providing for continuously circulating a heat interchanging liquid from the tank 14 through the intermediate chamber 5 about the vertical pipes 8. 19 designates an electric motor for operating the pump 19.

In practicing the invention, the sand to be pre-conditioned is continuously supplied to the receiving vessel 4. In the drawing, a chute 20 is shown for delivering the sand to the receiving vessel. The sand delivered to the receiving vessel, enters the upper ends of the vertical pipes 8, the sand being thus divided into a multiplicity of small streams and falls by gravity through the vertical pipes 8. As will be understood, if the temperature of the sand is to be lowered, and cold water is circulated through the chamber 5 about the pipes 8, the cold water takes up heat from the sand as the same passes through the vertical pipes and in contact with the walls thereof so that the sand after passing through the vertical pipes is in a cool state suitable for mixing with the other ingredients of the concrete mix. If the temperature of the sand is to be raised, and hot water is circulated through the chamber 5, heat from the water is transmitted to the sand, the temperature of the sand being thus raised to the desired degree suitable for mixing with the other ingredients of the concrete mix. The pre-conditioned sand flowing from the vertical pipes is received in the lower compartment 6 from which it is discharged through the opening 18 onto an endless carrier 21 and conveyed thereby to the mixing plant, not shown.

While a preferred form of apparatus is illustrated in the drawing, it will be understood that minor changes and modifications may be made in the particular construction shown and the apparatus may take other forms, as will appeal to those skilled in the art and falling within the scope of the appended claims without departing from the spirit of the invention.

In instances where cold water is available from natural sources, the invention contemplates making use of this for supplying the chamber 5 with cold water, in such instances the cooling unit hereinbefore described being dispensed with. The tank 14 is provided with an additional inlet pipe connection for the natural cold water sup-

ply, and the tank is also provided with an additional valve controlled overflow pipe to serve as a waste pipe.

What I claim is:

- 5 1. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank for cooling the liquid therein, liquid heating means connected with the tank for heating the liquid therein, means for closing off communication between the cooling coil and the refrigerating unit and means for closing off communication between the liquid heating means and the tank whereby the refrigerating unit and the liquid heating means may be operated independently of each other, a pipe connection between the tank and the lower part of said chamber, a pump interposed in said connection for forcing liquid from the tank to said chamber, and a return pipe connection between the upper part of said chamber and said tank.
- 20 2. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 25 3. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 30 4. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 35 5. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 40 6. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 45 7. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
- 50 8. In an apparatus for altering the temperature of sand and like granular material, including a vessel open at its upper end for receiving granular material to be treated, an elongated, vertically disposed closed chamber beneath said receiving vessel for a temperature interchanging liquid, vertical pipes extending through said closed chamber and communicating at their upper ends with said vessel at the bottom thereof, a tank, a temperature interchanging liquid in said tank, a refrigerating unit having a cooling coil located within the tank, pipes connecting opposite ends of the cooling coil with the refrigerating unit, a cut-off valve in each of said pipes, a liquid heating unit, a pair of pipes connecting the liquid heating unit with said tank, a cut-off valve in each of the last mentioned pipes, a pipe connection between the tank and the lower part of said chamber, a pump interposed in said connection for forcing liquid from the tank to said chamber, and a return pipe connection between the upper part of the chamber and the tank.
